UNITED STATES PATENT OFFICE.

RALPH R. CROCKER, OF COUNCIL BLUFFS, IOWA.

PACKING CONNECTION.

1,411,205.

Specification of Letters Patent. Patented Mar. 28, 1922.

Application filed December 19, 1919. Serial No. 346,033.

To all whom it may concern:

Be it known that I, RALPH R. CROCKER, a citizen of the United States, residing in the city of Council Bluffs, in the county of Pottawattamie and State of Iowa, have invented 55 certain new and useful Improvements in Packing Connections, and have described the same in the following specification, illustrated by the accompanying drawings.

10 My invention relates to a non-leakable connection between telescoping pipes, or other pipes, or between a pipe or a pump casing and a container of a gaseous or liquid fluid, and to packing devices which are 15 adapted to be used in connection with piston-rods, regulator rods, pump plungers, slide valve stems, and the like, and individually comprise a tubular casing and a follower adjustable therein. It is the main 20 object of the invention to adapt a packing device to connect with the inside of a barrel or like receptacle imperviously and without leakage; to render a single packing connection applicable alternatively to different cyl- 25 inders, pump tubes and casings, steam dome casings and other containers, as convenience may require; to adapt a packing connection, when applied to a barrel or other container, as a pump head or as a holder of a pump 30 casing, to hold the pump or casing immovably in its given or desired position in the container; and in general to increase the adaptability and efficiency of packing connections. To accomplish this object, I in- 35 corporate in my improved packing connection as part thereof, a stuffing box which has a gland in one end and is formed with external screw threads on the other end and with internal screw threads at each end.

40 In said drawings, illustrating the best manner in which I have contemplated applying the principles of the invention, Fig. 1 is a side elevation of a packing connection which is constructed in accordance with 45 these principles. Fig. 2 is an axial section of the same, with two pipes joined thereby. Fig. 3 is an axial section of a modified form of the device, applied to a tank or similar container.

50 In these drawings the stuffing box proper is a hollow casting, of general cylindrical form, which is denoted in Figures 1 and 2 by the numeral 1, and in Fig. 3 by 1'. Ex-

ternally it is formed with a projecting angular formation 2 for engagement with a wrench, and with the screw threads 3 on that end of the box which for convenience may be termed its inner or lower end. Internally it has the axial bore 4 and the central coaxial chamber 5 which is larger than the bore. It has also in its opposite end portions the cylindrical chambers 6 and 7, which are coaxial with the bore and internally screw-threaded. The gland or follower 8 is tubular and externally screw-threaded. It 60 has an angular top flange 9 for engagement with a wrench, and a central bore continuous with the bore 4 as well as of the same diameter, and is adapted to act upon the fibrous stuffing 10 in the chamber 6. In the 65 modification shown in Fig. 3, the box, 1', is provided with an outlet port 14 and a radially directed nipple 11, which leads from the chamber 5 and is adapted to connect with a delivery pipe. In the use of this modification as a pump-head, space around the pump 70 rod must be allowed in the bore 4 between the chambers 5 and 7 for the passage of the pumped fluid up into the chamber 5 from the pump casing below.

75 Such being the construction of the device, its applicability and operation are now to be explained. It may be applied to a dome casing, a barrel, a tank or other container of a liquid or gaseous fluid, and imperviously united with the container, by screwing it into a bung-hole, or screw-threaded aperture of the container 12, as shown in Fig. 3, and may be transferred successively from one such position or container to another, as 80 may be desired. It may be applied to a pump casing 13 in any desired position of longitudinal adjustment thereon, as shown in Fig. 2, and may be held immovably in that position by screwing down the gland 8 85 upon the stuffing 10.

I claim as my invention—

1. In a packing connection a stuffing-box having an axial bore, an external screw thread, a central chamber larger than the bore, and an internally threaded opening, larger than the bore and coaxial therewith, in each end of the box.

100 2. A packing connection comprising a stuffing-box having an external screw thread, an axial bore, a middle chamber

larger than the bore, an outlet from the middle chamber, and an internally threaded chamber in each end of the box.

3. A packing connection comprising a 5 stuffing-box having an axial bore, a central chamber larger than the bore, an outlet from the chamber through the side of the box, an external screw thread on one end of the

box, an internal screw thread in each end of the box, packing material in the box, and 10 a screw-threaded tubular gland working on the internal thread to compress the packing.

Witness my signature at Omaha, Nebraska.
